UNITED STATES PATENT OFFICE.

EDWARD LESLIE, OF ORANGEVILLE, ONTARIO, CANADA.

ROTARY EXCAVATOR FOR REMOVING SNOW.

SPECIFICATION forming part of Letters Patent No. 380,809, dated April 10, 1888.

Application filed August 31, 1887. Serial No. 248,367. (No model.)

To all whom it may concern:

Be it known that I, EDWARD LESLIE, of Orangeville, in the county of Dufferin, Province of Ontario, and Dominion of Canada, have 5 invented a new and Improved Rotary Excavator for Removing Snow, of which the following is a full, clear, and exact description.

My invention relates to a rotary excavator for removing snow, for which United States 10 Letters Patent No. 338,759, dated March 30, 1886, were granted to me.

The object of my present invention is to provide a new and improved excavator which very effectively and rapidly removes the snow 15 from the track and prevents all clogging of the working parts.

The invention consists in the construction and arrangement of parts and details and combinations of the same, as hereinafter more 20 fully described, and pointed out in the claims.

Reference is to be had to the accompanying drawings, forming a part of this specification, in which similar letters of reference indicate 25 corresponding parts in all the figures.

Figure 1 is a front elevation of my improvement, parts being removed. Fig. 2 is a sectional side elevation of the same on the line $x-x$ of Fig. 1. Fig. 3 is a sectional plan view of one of the knives of the upper set of knives 30 on the line $y-y$ of Fig. 1, and Fig. 4 is a like view of one of the knives of the lower set of knives on the line $z-z$ of Fig. 1.

My improved excavator is mounted on a car, on the forward end of which is fixed a 35 cylindrical casing, A, provided in its front with a square hood, B, having flaring edges, which extend from the level of the track to a suitable height and at each side for a considerable distance, so as to form an opening 40 through the snow large enough for the car to pass through. In suitable bearings on the car is placed a horizontal shaft, C, which extends forward through the center of the casing A, and has upon its outer end a wheel, D, rotating 45 in said casing A. The wheel D is provided with a hub, E, secured to said shaft C, and on the inner end of the hub E is fastened the circular plate F, placed near the inner wall of the casing A, but not touching the 50 same.

To the front of the hub E is secured a second hub, G, provided in front with the cone

H, extending a suitable distance into the flaring hood B. From the hub G extend the spokes G', on which is secured a ring, I, and 55 radial fans or wings J extend from the front of said ring I to the inner disk, F, to which they are also secured. The front top ends of the fans J are covered by a ring, K, secured to said fans in any suitable manner. 60

Midway between each two successive fans, J, is placed a radial shaft or rod, L, secured by bolts or other means to the rings I and K. On each shaft or rod L is held to swing a knife, N, provided with two wings, N' and N'', placed 65 at angles to each other, as shown in Fig. 3. The edges of the knife-wings N' and N'' extend radially in line with the respective fans J and rest against the same. It will be seen that when the knife edge of one wing of the knife 70 N rests against its respective fan J then the knife-edge of the other wing of said knife extends a suitable distance from its respective fan, so as to form an opening into the interior of the wheel between the radial shaft or rod L 75 and the outer edge of the respective fan J.

Between two successive spokes, G', of the hub G is placed a radial shaft or rod, O, secured by one end to said hub and by its other end to the ring I. On said shaft or rod O is held to 80 turn a knife, P, similar in construction to the knife N, and provided with wings P' and P'', extending at angles to each other, so that when the radial cutting-edge of one wing rests against its respective spoke G' then the cutting-edge of the other wing or knife, P, extends a suitable distance from its respective spoke G', thus forming an opening in the front of the wheel, which leads into the interior of the 85 same, said opening extending from the shaft or rod O toward the respective spokes G'. 90

As illustrated in the drawings, I have not quite as many knives P in the inner set as in the outer set. Instead of continuing the knives N to within a short distance of the hub 95 G, I provide a second set of knives, P, which, in consequence of there being only half the number in this set, are made larger in proportion. As illustrated, two outer knives are employed to one inner knife; but I may vary 100 the relative number of the two sets, so that, for instance, I may use three outer knives to one inner knife, whereby I reach still farther to the front, and thereby increase the opening.

The operation is as follows: When the shaft C is rotated in the direction of the arrow a', then the sets of knives N and P open their wings N² and P², respectively, while the other 5 wings, N' and P', are closed and rest with the outer edge against the fan J or the spoke G', respectively. The snow thus passes into the opening formed by the wings of the set of knives N and P, and the snow in the center of 10 the hood B is pushed by the cone H up toward and into the opening formed by the lower set of knives, P. The snow, after entering the wheel D, is forced out of the same by the fan J into the spout Q, which leads the snow to 15 one side of the railroad-track. When the motion of the shaft C is reversed, then the wings P² and N² of the knives N and P close, whereby the wings N' and P' are open, and the above operation is repeated in the same manner.

20 It will be seen that with my inner set of knives I provide a greater capacity for taking in the snow in the center of the wheel, at the same time gathering the snow which passes up the cone on the front hub.

25 The opening formed by the inner set of knives being greater than the opening at the inner edge of the outer knives, permits the wheel when rotated in the snow to bore out the center of the latter, thereby allowing the 30 snow to contract from the flaring edges of the hood, thus relieving the latter from excessive strain, especially in hard-frozen snow.

Having thus fully described my invention, I claim as new and desire to secure by Letters 35 Patent—

1. In an excavator, a revolving wheel provided with radial fans, an outer set of knives, and an inner set of knives, both sets of knives being held in front of said wheel, substantially as described.

2. In an excavator, the combination, with a 40 revolving wheel provided with radial fans and

a cone in its center in front, of an outer set of knives held in front of said wheel and in front of the fans, and a second or inner set of knives 45 forming an opening to the inside of the wheel, substantially as shown and described.

3. In an excavator, the combination, with a revolving wheel provided with a hub carrying an inner disk, of a second hub fastened to the 50 front of the first-mentioned hub, and having radial arms or spokes, a ring secured to said radial arms or spokes, radial fans secured to said ring and to said disk, an outer ring held in front of said fans, and two sets of knives, 55 of which the outer set is held in front of said fans and the other set is held between the inner ring and the hub, substantially as described.

4. In an excavator, the combination, with a 60 revolving wheel provided with a hub carrying an inner disk, of a second hub fastened to the front end of the first-named hub and having radial arms or spokes, a ring secured to said radial arms or spokes, radial fans secured to 65 said ring and to said disk, an outer ring held in front of said fans, two sets of knives, of which the outer set is held in front of said fans and the other set is held between the inner ring and the hub, and a cone held in front 70 of the second hub so that the snow from the center passes into the inner set of knives, substantially as shown and described.

5. In an excavator, the combination, with a 75 revolving wheel, of radial fans held on said wheel, an outer set of self-reversing knives held in front of said wheel and an inner set of self-reversing knives held similarly on the said wheel, substantially as described.

EDWARD LESLIE.
